UNITED STATES PATENT OFFICE.

JOHN KRUTTSCHNITT, OF NEW YORK, N. Y.

TIER.

Application filed January 12, 1920. Serial No. 350,791.

To all whom it may concern:

Be it known that I, JOHN KRUTTSCHNITT, a citizen of the United States, residing in the borough of Manhattan, city, county, and State of New York, have invented certain new and useful Improvements in Tiers, of which the following is a specification.

This invention relates to a tier for ropes, cords, and other cordage, including wires, and has for its object to provide a device of this character adapted for use where it is desired to employ the hitch known as the Blackwall. It is equally well adapted as a package tie for use with light cord, or as a bale tie for use with wire, or as a rope tie for use with lines generally.

Its further object is to provide a device of this character of simple and cheap construction, capable of repeated use, and which will afford greater security in tying the Blackwall hitch, so that while such hitch may be easily cast off when the strain is relieved, it will not become easily detached by unintentional relaxing of such strain, as is the case with the hitch when tied upon an ordinary hook.

A further object is to permit the ready release of the cordage, and when used as a package tie a firm securing of the ends of the cord without knotting the cord.

These and further objects of the invention hereinafter detailed are realized by the several embodiments thereof illustrated in the accompanying drawings forming part of this specification, in which Fig. 1 is a perspective view of a section of a tent having an extension to its top in the form of a fly engaged by my improved tier, to which is attached a rope passed over a tent peg in the usual manner, the four successive steps in tying the Blackwall hitch being illustrated as applied to the series of hooks shown in its several stages. Fig. 2 is a side view in elevation of the tier of Fig. 1, Fig. 3 showing the tier of Fig. 2 when viewed at right angles to the position shown in Fig. 2 and also in elevation. In Figs. 1, 2 and 3 the tier is shown as composed of a wire or rod appropriately bent. Fig. 4 is a perspective view of the tier in substantially the same form, as previously illustrated, made by casting. Fig. 5 shows the application of the form of tier illustrated in Figs. 6 and 7 as composed of a bent wire or rod with an eye formed therein in lieu of the hook shown in prior figures. Fig. 5 shows the form of

application of this tier to a fixture for engaging the eye thereof, with a line bent thereabout. Fig. 6 is an elevational view, and Fig. 7 is a view at right angles thereto. Fig. 8 is an illustration of the type of hook shown in Figs. 5, 6 and 7, of cast form, the rope shown in association therewith being tied in a Blackwall hitch, part of the rope being cut away to appear in section to show the relative position of the tier and of the rope as engaged therewith. Figs. 9 and 10 show the adaptation of my invention to a hook form of tier provided with an eye, Fig. 9 showing same in elevation and Fig. 10 being a view at right angles thereto. Figs. 11 and 12 show the application of the form of hook illustrated in Figs. 13 and 14 as a package tie. Fig. 13 is an elevational view of the tie formed from a rod or wire of spring metal. Fig. 14 is a view at right angles thereto. Fig. 11 shows a package with a cord thereabout, one end of the cord being engaged in the open eye of the spring shank and clamped thereby when the Blackwall hitch is formed and tightened, as shown in Fig. 12. Figs. 15 and 16 illustrate the application of the form of hook shown in Figs. 17 and 18 to a package as a four-way tie, Fig. 17 showing the perspective elevation of the tie in this form, and Fig. 18 an elevation at right angles thereto. Fig. 15 shows the method of tying the Blackwall hitch thereupon, and Fig. 16 the means provided by the hook for securing the cord when passed about the package at right angles to the direction of the cord forming the hitch. Fig. 19 is a modified form of tie, preferably formed as a metal stamping, and is intended for use with wire or wire rope, as for example in a cotton bale tie. Fig. 20 is a further modification showing in elevation a duplex tie, the shank engaging the tie elements being offset to permit of strain being exerted in the same line as shown when a Blackwall is formed at each end thereof, as illustrated.

Throughout the several figures like numerals of reference are used to indicate corresponding parts.

Referring to Figs. 1, 2 and 3, 1 is the shank of the tier, in this case formed of a metallic rod bent upon itself and having the closed end bent downwardly to form the hook 4, and having the two free ends bent upwardly to form the respective hooks 2 and 3, the hook 2 having a shorter shank than

the hook 3, so that the two hooks are relatively disposed in the same plane and are mutually offset in a relatively diagonal direction for the purpose hereinafter explained. The hook 4 is adapted to engage an eye and is shown in Fig. 1 as engaging the extended edge of a tent cover 6. The hook members 2, 3 are particularly adapted to co-operate with a rope in the formation of the hitch known as the Blackwall. The successive steps of tying the Blackwall hitch are illustrated in Fig. 1 in a series of positions indicated by the letters A, B, C and D. The rope 5, being first attached to a tent peg or the like, is passed over the shank and below the hooks, as shown at A. The free end of the rope is then passed between the hook 3 and the rope engaged therewith, as shown at B. It is then passed upwardly and over the hook 3 and in contact therewith, as shown at C, and is then brought downwardly between the bight of the hook and the rope, as shown at D, and tightened, so that the strain upon the length of rope engaging the tent peg jams the free end of the rope against the bight of the hook, from which it may be easily detached when desired. By forming the hooks at unequal heights the tendency of the hitch to relieve itself when the strain is unintentionally relaxed is overcome as the loop end of the rope passing about the shank of the hook is prevented from slipping down by its engagement with the hook 2, thereby preserving the line of strain and applying the force thereof more directly to the jammed end of the rope, promoting the security of the hitch and its permanence until intentionally cast off. In the modification shown in Figs. 5 to 7, inclusive, the tier is shown as composed of spring metal, and the means for permanent attachment in lieu of the hook form shown as 4 in Fig. 2, is substituted by the eye 7. The material being of spring metal, the shanks of the hooks may be spread to permit access to the eye, or cordage may be passed directly through the eye, all elements of the tier lying in the same plane.

In Fig. 8 the bight of the lower hook is shown as substantially of the configuration of the cord to be jammed therein, the curvature of the concavity of the hook 3 approximating the radius of the cord to be engaged, a construction which may be found desirable under certain conditions of use. Figs. 8 to 10, inclusive, illustrate the modification of my invention relatively to Figs. 5 to 7, inclusive, which Fig. 4 bears to the form shown in Figs. 1 to 3, inclusive; that is, instead of forming the tie from a metallic rod by bending same, it may be formed by casting with

the solid shank as a single piece of metal.

In Figs. 11 to 18, inclusive, the tier shown is in modified form, in which, in lieu of the eye 7, an open slot or eye is formed between the respective shanks 8 and 9 of the hooks 2 and 3. The spring of the metal is utilized to clamp therebetween the free end 10 of the cord passed about the package 11, the shanks being clamped thereon by the tightening of the hitch so that no knotting of the cord is necessary. A like adaptation is employed in the forms illustrated in Figs. 17 and 18. In this extension of the invention the hooks 2 and 3 have extended offsets 12 and 13 adapted to receive and retain the cord 14, as shown in Fig. 16, in the form of a supplemental hitch thereabout, the strain of the second hitch being at right angles to the strain of the first. In Fig. 19 is shown an adaptation of the tier to the special utilities of engagement with a wire or wire rope, as for example in a cotton bale tie. This form permits a particularly economical manufacture as it is a metal stamping whose edges are objectionable for use as a cordage tie but better adapted for the purpose of engagement with wire. The tier 15 here shown is a unitary piece of metal engaging the wire 16 by the eye formed therein, which wire is then adapted to be passed about a bale and tied in a Blackwall around the loops 2 and 3 and hitched thereto. In the extension of the invention shown in Fig. 20, a duplication of the hitching hooks is shown as terminating a common shank 17 which is offset so that the strain of the pair of hitches is alined, whereby the permanence of each is assured.

Having thus described my invention and several of its physical embodiments for special uses, which do not involve a departure from the specific intent and purpose of the invention, namely, to provide a tying device for accomplishing a new and better method of securing the Blackwall hitch, I claim as new and desire to secure by Letters Patent the following:

A tier for a Blackwall hitch, comprising a shank, a hook associated with said shank and adapted to provide a seat for the crossed portion of a Blackwall hitch, and another hook on the opposite side of said shank elevated above the first mentioned hook and adapted to form a seat for the loop portion of the Blackwall hitch, said seats being so positioned relatively as to cause the crossing portions of such hitch to have a relatively long contact surface, while permitting facile passage of the under strand beneath the upper strand during the maintenance of relatively great strain on the rope.

JOHN KRUTTSCHNITT.
